UNITED STATES PATENT OFFICE.

COLLINGWOOD CAMPBELL, OF WEST BAY CITY, ASSIGNOR OF ONE-HALF
TO JAMES E. THOMAS, OF BAY CITY, MICHIGAN.

SAW-SWAGING MACHINE.

SPECIFICATION forming part of Letters Patent No. 355,379, dated January 4, 1887.

Application filed July 21, 1886. Serial No. 209,608. (No model.)

To all whom it may concern:

Be it known that I, COLLINGWOOD CAMPBELL, a citizen of the United States, residing at West Bay City, in the county of Bay and State of Michigan, have invented certain new and useful Improvements in Saw-Swaging Machines, of which the following is a specification, reference being had therein to the accompanying drawings.

This invention relates to improvements in saw-swaging machines of that class which are clamped to a saw-tooth and provided with a die and anvil which operate to spread the point of the saw-tooth in lateral directions and form a cutting-edge which is wider than the thickness of the saw, and which operates when cutting to form a saw-kerf of sufficient width to give the proper clearance to the saw.

The invention consists, chiefly, in the combination and arrangement of a suitable holder and devices for securing the holder to the saw, a cylinder passing through the holder and provided with a longitudinal opening carrying a cylindrical die and anvil inclosed in the holder, and devices for adjusting the anvil to the die; and the object of my invention is to provide a machine for swaging the teeth of saws which will operate with great ease, and that will spread the cutting-face of the saw-tooth in a manner to reduce the liability of breaking the edges thereof, and that will form a more perfect cutting-point upon the tooth by operating upon the tooth in a manner to roll out the material thereof, instead of spreading the point of the tooth by direct pressure. The devices which I employ to attain these objects are illustrated in the accompanying drawings.

Figure 1 is a side view of my improved device. Fig. 2 is a view of the opposite side of the same. Fig. 3 is a vertical section of Fig. 1. Fig. 4 is a section of Fig. 3 through $x-x$. Fig. 5 is a section through $y-y$. Figs. 6 and 7 are views of the cylindrical die-holder detached. Fig. 8 is an enlarged view of the die detached.

a represents a holder of circular form, for convenience, the lower portion of which is provided with a slot, b , formed transversely with the diameter of the holder, and forming

a solid portion, d , on opposite sides of the slot, through which are passed the clamping-bolts c and e , provided with suitable heads and a wrench or lever, f , with which to turn the screws. Through the central portion of the holder is formed an opening, g , the lower portion of the opening reaching into the slot b , and a cylindrical die-holder, i , is placed in the opening, and is arranged with the cylindrical portion reaching to the side faces of the holder a , and with the portions j projecting beyond the side faces of the holder; and one or more levers k are firmly secured to the portions j , and, extending beyond the outer edge of the holder, are bent inwardly and form a single arm, l .

The portion of the cylinder i passing through the slot d when the cylinder is in position in the holder a is cut away, forming a slot, m , and leaving a portion, n , about one-third of the size of the cylinder solid; and a longitudinal opening, o , is formed in the die-holder or cylinder, and is located a short distance on one side of the center of the cylinder and passes through the slot m , and is about one-half its diameter into the solid portion n . A cylindrical die, p , is placed into this opening o , and is of a proper length to reach for a short distance on each side of the slot m , leaving a die-face, h , exposed in the slot, and is held loosely in position by a screw, q , passed into the outer end of the opening o . This opening o may extend entirely through the die-holder, if required, and a screw, q' , is then placed in the opposite end of the opening. These screws loosely secure the die in place and allow a longitudinal adjustment of the die p , so that the portion of the die exposed by the slot m and forming a die-face, h , may be changed by moving the die slightly endwise.

A radial opening, e' , is formed through the upper portion of the holder a , and extends entirely into the slot b in a line diagonal to the upper portion of the slot, and an anvil-die, u , having a die-face, v , diagonal with its body, is placed within the opening e' , and the lower portion, f' , is cut away on its sides to a proper size to allow it to pass within the slot m , and its upper portion is provided with a spindle, g' , and surrounding the spindle g' is

a sleeve, *h*', which is provided on its outer surface with a screw-thread and is passed into the opening *e*', the opening *e*' being provided with a screw-thread. The die *u* reaches into the slot *m*, and the screw-threaded sleeve then holds the die in position and allows the die-face to be adjusted to a proper position in relation to the die *p*.

When the die *u* is properly adjusted, the block *a* is placed upon the saw with the saw-tooth resting within the slot *b*, and with the back or upper edge of the tooth to be operated upon resting against the die-face *v*, and with its front or cutting edge resting against the face *h* of the die *p*. The clamping-screws *c* and *e* are then adjusted to firmly hold the tooth in position, and then the levers *k* are operated to rotate the die-holder *i* in the direction indicated by the arrows, and the die *p*, being located on one side of the center of the holder *i*, engages with the saw-tooth considerably below its point, and as the holder is revolved the die rolls toward the point of the tooth, and at the same time presses into the tooth, forming a recess into the tooth and spreading out laterally the point or cutting portion of the tooth to a width considerably greater than the thickness of the saw-plate. The points of the teeth are then slightly dressed and fitted up with a file, and the saw has a free and easy clearance in the log.

The advantage of this form of die-holder is, that the die, being held loosely in position in the holder, is allowed to revolve as the die moves toward the point of the tooth, which has the effect of reducing the friction, and also leaves the metal in the point of the tooth in better condition, as the original temper of the steel is retained, and it also forms a different impression-tooth from an ordinary swaging-die, beginning farther from the point and moving forward, forming a deeper impression as it nears the point, and leaves the tooth longer than before the swaging operation was performed.

The die *P* may be formed with an even or straight cylindrical surface, or have an irregular face, as shown in Figs. 4, 8, and 7. In Fig. 4 is shown the die-face formed with two reduced portions, *r*, on the outer portions of the die-face, and with the reduced part *s* located centrally between the portions *r*. This construction forms the heavier portions *t* between the portions *r* and *s*, which operate to spread the sides of the saw-tooth by making a heavier impression upon each side of the center of the saw-tooth, and leaves a fuller portion in central part of the die-impression, which operates to prevent splitting the tooth by the swaging operation.

In some cases—as with thin saws—the central depression, *s*, may be left out, as shown in Fig. 7, and produce a better result, as the material will be sufficiently spread with a lighter impression upon the tooth.

Around the holder *a* is a band, *i'*, one end of which is bent outward and forms an arm,

j', and the other end, *k'*, reaches outward upon the arm *j'* for a short distance, and is secured thereto by a bolt, *l*, a small space being left 70 between the part *k'* and the arm *j'*, which allows the bolt *l* to draw the parts together and clasp the band *i'* firmly around the holder, so that the extended arm *j'* may be secured in any desired position. The outer end of this 75 arm *j'* is provided with a portion, *m'*, extending from its side, which bears upon the point of a tooth which has been swaged, and operates to bring the holder to the same position on every tooth.

I do not confine my invention entirely to the form and construction of the upper die, *u*, nor to the devices shown for clamping the holder to the saw, as other devices may be used for these purposes and answer equally as 85 well; but

What I claim as my invention, and desire to secure by Letters Patent, is—

1. In a saw-swage, the combination, with a cylindrical die-holder having a longitudinal 90 opening on one side of its center and a transverse slot in the middle of its length, of a cylindrical die placed in the said longitudinal opening and extending across the said slot, substantially as and for the purpose set forth. 95

2. In a saw-swage, a cylindrical revolving die having a die-face extending entirely around its central portion, and consisting of the reduced portions *r* on each end portion of the face and the reduced portion *s* in the central portion of the face, substantially as and for the purpose set forth. 100

3. In a saw-swage, the combination, with a holder, *a*, provided with devices for clamping the holder to the saw, and an anvil-die supported by the holder, of a cylindrical die-holder passed through the holder *a* and provided with a longitudinal opening in one side of its center, and having a transverse slot in the middle of its length and reaching into the said longitudinal opening, and a cylindrical die placed into the said opening and extending across the slot, substantially as and for the purpose set forth. 105

4. In a saw-swage, the combination, with a 110 cylindrical die-holder having a longitudinal opening on one side of its center and a transverse slot in the middle of its length and reaching to the said opening, and a cylindrical die within the opening and extending across the 115 slot, of a screw passed into the end of the said longitudinal opening and with its inner end against the die, substantially as and for the purpose set forth. 120

5. In a saw-swage, the combination, with a 125 cylindrical die-holder provided with a transverse slot in the middle of its length and a longitudinal opening in one side of its center, and a cylindrical die within the opening, of an anvil-die having a portion reaching into 130 the said slot and provided with a die-face, substantially as and for the purpose herein set forth.

6. In a saw-swage, the combination, with

holder *a*, provided with devices for clamping the holder to the saw-tooth, and a cylindrical die-holder provided with a cylindrical die on one side of its center and a transverse slot on one side of the cylinder opening to the die-face, of an anvil-die, *u*, having a portion, *f'*, extending into the said slot and provided with a die-face, a spindle, *g'*, extending through the upper portion of the holder *a*, and a sleeve, *h'*, surrounding the spindle and secured to the holder *a* by a screw-thread, substantially as and for the purpose set forth.

7. In a saw-swage, a cylindrical die-holder having a longitudinal opening in one side of its center and a transverse slot in the middle of its length and reaching to the opening, in combination with a cylindrical die reaching across the slot and loosely secured within the

said opening, whereby the die revolves in one direction and the holder in the opposite direction when operating on the saw-tooth, substantially as set forth. 20

8. In a saw-swage, the combination, with a holder, *a*, and devices for clamping the holder to the saw, and a die-holder passing through the holder *a* and provided with a cylindrical die, of a band, *i'*, surrounding the holder and provided with the arm *j'* and the extension *k'*, and the bolt *l'*, passed through the arm and extension, substantially as herein set forth. 25 30

In testimony whereof I affix my signature in presence of two witnesses.

COLLINGWOOD CAMPBELL.
